MEANS FOR MAKING FILLERS FOR RUGS

Romeo Paulus, Plainville, Mass.

Application July 25, 1940, Serial No. 347,443

1 Claim. (Cl. 19—105)

The present invention relates to a means and method of making filler for rugs and the like, in particular for tubular rugs in which a tube or shell is braided around the filler after which the tubes are coiled helically or in some other fashion and permanently joined by stitching the sides of the walls together.

The customary method is to use a number of filler strands together and to braid these into a single filler after which the filler is fed into the 10 braiding machine where a cover is braided around it. In some cases the filler strands or rovings as they are called, are not braided but laid flat together. It must be remembered that for the most part the roving strands or filler is made up of short length fibres such as old wool or scraps and that inherently the strands so made have no strength and therefore cannot be worked to any great extent.

In the present invention the roving strands, 20 may or may not be braided before the cover is braided over the filler in the braiding machine. The condenser however commonly used in condensing the roving strands is entirely eliminated and instead the fibres themselves are given a greater twist than is customary and thereby a stronger yarn or strand is made.

In the present invention this is accomplished by splitting the main card in two and drawing off the roving or strand from both ends of the machine in a side draw. The speed of drawing off for any one machine is thereby cut in halves and the strands or fibres are less pulled out thereby permitting and giving the fibres a greater twist in forming the strands.

In fact the improved rovings or strands are sufficiently strong so that they need not be compressed in a condenser and further they may be braided instead of being merely laid together and handled in the usual way in the process of making the rugs.

In the present invention the usual carding machine may be used, either in single sections or in repeated sections with more than one breast roller. In this machine the rollers are usually more than seventy-two inches long and they are fed from a feeder and breaker over a feed lattice to a system of rollers which have become quite standard in the industry of carding and forming of yarns.

The rollers in the system or unit all have a definitely established purpose and in the present invention therefore these are shown more or less diagrammatically.

The present invention in this respect relates 55

chiefly to the manufacture of loosely held filler for the braided casings used in making tubular rugs and will be described more particularly in connection with the drawings, in which:

Figure 1 shows diagrammatically in elevation the system partly in section.

Figure 2 shows a plan view of the system as viewed from the top of Figure 1 with a fragment in section, and,

Figure 3 shows a detail.

In the system shown in Figure 1 the scrap wool is put in the feeder 1 which breaks up the wool into shreds in the usual fashion and deposits it from the hopper 2 on to the guides 3 and 4 to the feed lattice 5 which carries the wool in broken form to the feed rollers 6, 7 and 8. These feed rollers pass the wool to the "licker in" roll 9 which is covered with Garnet wire in the usual fashion. Associated with these rolls is the angle stripper 10 which passes the wool on to the breast or swift roll 11. All around the large breast roll are grouped workers, 12, 12, 12, and strippers 13, 13, etc., until the last of the small group of rolls is reached 14, which is called the fancy, the purpose of which is to prepare the wool on the breast roll by bringing it to the surface so that it can be removed by the doffer roll 15. Where one unit is used, the wool may be removed from the doffer, but it is customary in many cases to card the wool through a second set of rollers similar to the first set as indicated in Figure 1. In this case the wool is passed on through the second breast or swift roll 16, until finally the wool reaches the second doffer 17 after it has been combed by the comb 18. The wool may be drawn off by a side draw as is done in the present case by means of the tapered roller 19, the function of which will be more fully described below.

In the present system as indicated more clearly in Figure 2, the hopper 2 is formed with a partition 20 in which no wool is allowed to fall. Therefore as the wool is fed down on the guides 3 and 4 to the lattice 5, the center portion 21 is free from the woolen fibres. The rollers 6, 7 and 8 transfer the fibres to the "licker in" 9 which is wound with Garnet wire except in the center portion 22 which is smooth and has no wire on it and is therefore away and clear of the feed rollers at this point. The breast roll 11 and the workers and strippers 12 and 13 are constructed in the usual fashion and in fact the rest of the machine is of the usual construction until the last doffer 17 is reached. The separation however of the wool by means of the par-

tition in the feeder box 2 and the free space 22 on the "licker in" 8 keeps the wool transferring in two separate and distinct sections over the whole breast roll system so that when the wool fibers come to the end of the system, the center section of the doffer 17 is free and clear of any wool.

In the present invention the end roll 18 is tapered from the center point 23 outward to the ends 24, 24, where the filler is drawn off through the rotating tapered tubes 25 and the draw off rollers 26 and 27 between which the filler is pulled.

An enlargement of the end rollers is shown in Figure 3, where the end 24 of the tapered roll and the doffer roll 17 pass the filler to the trumpet tube 25 which is rotated by means of a pulley 28 usually driven in conjunction with the drive for the other rollers in the system. One of the draw rolls 26 is larger than the other roll 27.

The purpose of the whole carding system is to line up the wool fibers along the peripheral direction of rotation of the rolls so that all the fibers are lined up in the same way. When the fibers come to the last doffer roll 17 they tend to curl up in the space between the tapered roll 18 and the doffer roll 17. The drawing of the filler at the side tends to pull these fibers out longitudinally, parallel with the axis of the roll so that the fibers in general are given a spiral twist as the filler is drawn off through the draw rolls 26 and 27. If these fibers are drawn off very rapidly, as they must, if the feed is rapid, the longitudinal motion will be fast enough to line the

fibers longitudinally in the direction of the draw. Because the fibers are usually very short, this means that the strands or rovings have little strength. By twisting the fibers however, criss cross in the filler, as is done by slow drawing, the filler becomes stronger and can more readily be handled.

In the present invention this is accomplished by drawing half of the filler off each end of the roll so that the linear speed of drawing off for each filler can be cut in half. This not only permits the short fibers to be given a good cross twist, but also decreases the strain on the strand because the drawing off speed is reduced in half.

In place of partitioning the "licker in" 8, the feed rolls 6, 7 and 8 may be partitioned, and in fact if desired both the "licker in" 8 and the feed rolls may be partitioned in the manner described above. However the combination indicated has proved to be very satisfactory in attaching the usual apparatus for the present invention.

Having now described my invention, I claim:

In a carding machine for carding short wool fibers for filler strands, means partitioning the carding machine into two halves whereby the fibers on one half of the roll remain separated from the fibers on the other half of the roll, a final doffer roll, a tapered roll associated with said doffer roll tapered from a small center section outward to large end sections adjacent the end sections of the doffer roll and rotatable trumpet-like tubes for drawing the filler strands off at the ends of the doffer.

ROMEOPAULUS.
